UNITED STATES PATENT OFFICE.

IRVING CAESAR, OF NEW YORK, N. Y.

CANE.

Application filed July 22, 1926. Serial No. 124,225.

The present invention relates to improvements in handles of canes, umbrellas and the like, and has for its main object to provide a combination handle and portable lighter 5 wherein a frictional sparking device is employed.

Another object of the invention is to so construct the handle and the lighter that the wick forming part of the lighter may 10 be both ignited and extinguished while the cane or the like is held by one hand of the user, thus permitting the user to have one hand entirely free for handling the cigar or cigarette which is to be lit.

15 A further object of the invention is to provide a combination cane and lighter, the lighter element of which is disposed within the handle portion of the cane and concealed from view when not in use.

20 A still further object of the invention is to provide a contrivance of the character mentioned which is simple in construction, efficient in operation, durable in use and capable of manufacture on a commercial 25 scale, or in other words one which is not so difficult to make as to be beyond the reasonable cost of such a combination.

With these and other objects in view, which will more fully appear as the nature 30 of the invention is better understood, the same consists in the combination, arrangement and construction of parts hereinafter described, pointed out in the appended claim and illustrated in the accompanying drawings, it being understood that many changes 35 may be made in the size and proportion of the several parts and details of construction within the scope of the appended claim, without departing from the spirit or sacrificing any of the advantages of the invention.

One of the many possible embodiments of the invention is illustrated in the accompanying drawings, in which:

45 Figure 1 is an elevation of a combination cane handle and lighter constructed in accordance with the present invention; Fig. 2 is a similar elevation, partly in section, with the parts in open positions; Fig. 3 is a plan 50 view thereof with the parts also in open positions; Fig. 4 is a section taken on line 4-4 of Fig. 3; and Fig. 5 is an elevation, partly in section, of the lighter elements of the device.

55 In the drawings, the numeral 10 indicates a handle adapted for attachment to the staff

of a cane, parasol, umbrella or the like. This handle may be of any suitable shape, according to the requirements. In the case illustrated, the handle is provided with a 60 substantially semi-spherical grasping portion 11, which is hollowed out, as shown at 12, it being in the form of a cap which is attached to the body portion of the handle by a spring hinge 13, which tends to throw the said cap into open position, shown in Fig. 2 of the drawings. The upper section of the body portion 14 of the handle is also hollowed out, as shown at 15, to provide space for a lighter 16. The cap is held in 70 closing position, preferably, by a spring catch 17, the same being mounted in the hollowed out portion of the handle and designed to engage a projection 18 on the cap. The catch is adapted to be released by 75 a depressible button 19 on the body portion of the handle, so as to permit the cap to swing to an open position under the action of the spring hinge 13.

The lighter 16 comprises a casing 20, preferably of metal, the said casing being fitted into the hollowed out portion of the handle body. The top face 21 of the casing is disposed flush with the top edge of the handle body. Into the casing extends, as usual in devices of this type, a wick tube 22, the latter projecting above the top of the casing and its wick 23 being saturated with a liquid hydrocarbon, such as gasoline, which is stored within the casing. Above the casing top projects a post 24, on which is rigidly mounted a substantially horizontally extending tube 25, provided at its end, adjacent to the wick tube, with lugs 26, between which is rotatably mounted a friction disk 27 on a pivot pin 28. This friction disk is of hard metal, such as steel, and is roughened on its peripheral face, as shown at 29 in Figs. 2 and 5 of the drawings. A bar 25' of sparking material, preferably a pyrophoric alloy, is fitted loosely in the tube 25 and is pressed against the roughened periphery of the friction disk by any suitable means.

To the inner face of the cap is attached a flame extinguisher 30, in the form of a substantially cylindrical hollow body, having an open end 31, snugly fitting the free end of the wick tube, as clearly shown in Fig. 5 of the drawings. There is furthermore mounted within the cap 12 a sparking wheel protector 32, in the form of a cap-like body, which fits over the said sparking wheel

when the cap 12 is in closing position. This cap-like body is provided with a notch 33, in which the tube 25 is seated when the cap 12 of the handle is in its closing position.

5 The operation of this device is as follows: When it is desired to use the lighter, the button 19 is depressed, whereby the cap 12 springs automatically to open position. The user presses one finger of the hand, in 10 which the cane or the like is held, against the exposed periphery of the friction disk 27 and moves the said finger so as to rotate the friction disk in the direction of the arrow shown in Fig. 3 of the drawings, 15 whereupon a shower of sparks is driven from the pyrophoric material against the exposed portion of the wick, thereby igniting the latter. After using the device, the cover 12 of the handle is closed, whereby the 20 flame extinguisher 30 is brought into close engagement with the free end of the wick tube, thereby extinguishing the flame. At the same time the sparking wheel protector is swung over the latter.

25 It is obvious that, while herein a specific lighter construction has been described, any other may be used without departing from

the invention, which lies mainly in the provision of a can handle so constructed that the wick of the lighter may be lit and extinguished by using only that hand which holds the handle, and furthermore in so arranging the elements of the lighter that they are concealed from view when not in use.

30 35 What I claim is:—

A handle composed of a hollow body portion and a cap hinged thereto, a lighter fitted into said body portion comprising a casing, a wick tube projecting above the upper edge of said body portion, a friction disk rotatably mounted upon said casing adjacent the free end of said wick tube, a sparking element in engagement with said friction disk, a flame extinguisher attached to the inner face of said cap adapted to snugly fit the free end of said wick tube when said cap is in its closing position, and a cap-like body also mounted within said cap adapted to fit over said friction disk when said cap is in its closing position.

40 45 50 Signed at New York, in the county of New York and State of New York, this 18th day of May, A. D. 1926.

IRVING CAESAR.
